S. Ingersoll,

Hay Press,

No 19,811,

Patented Mar. 30, 1858.

UNITED STATES PATENT OFFICE.

S. INGERSOLL, OF BROOKLYN, NEW YORK, ASSIGNOR TO HIMSELF, S. B. TURNER, AND GEO. W. KIMBALL, ALL OF SAME PLACE.

IMPROVEMENT IN PRESSES.

Specification forming part of Letters Patent No. 19,811, dated March 30, 1858.

To all whom it may concern:

Be it known that I, SIMON INGERSOLL, of the city of Brooklyn, county of Kings, and State of New York, have invented a new and useful improvement in the construction of cotton, hay, and other presses that require considerable range in the follower, as well as a progressive power, and also that require a portable and compact press that can be used by hand or horse power, the novelty of which consists in the peculiar arrangement of the levers by which much space is saved on each end of the press-box, and also much room in its height, and allows the box to be made much stronger than by the common mode, and of using the same or similar levers, which saves the ends of the box from being slotted or left open, so that the levers can pass up and down when pressing; and I do declare that the following is a full, clear, and exact description of the same, reference being had to the annexed diagrams, making a part of this specification.

Figure 1 is a vertical section; Fig. 2, a top view of bottom beam, showing the position of and points where the levers are attached to the beams, also the connecting-chain and sheave. Fig. 3 is a top view of press, showing the lid and lever by which it is raised. Fig. 4 is a perspective view showing nearly all its points, reference being had to the letters marked thereon.

To enable others to make and use my invention, I will proceed to describe its construction and operation.

I construct my press-box in any convenient form that may be deemed best adapted to the work to be done, and attach my levers and beams, as hereinafter shown.

A A a a, Figs. 1, 3, 4, will represent press box and frame.

K is the bottom beam, on which the levers g g h h are pivoted, as shown at y y, Figs. 1 and 2. Beam K is fastened to the press-box by rods D D, which pass through end piece, A, Figs. 1 and 4, and secured by nuts on the bottom of beam K, as shown at B B, Fig. 1.

g h g h are the levers, as shown in Figs. 1 and 2, pivoted at c c', and placed on opposite sides of the beams E and K on pins y y.

E is the follow-beam, and F the follow-

board, board F being secured to beam E by bolts e' e', beam E being fastened to levers g g by bolts y y, Figs. 1 and 2.

J is a sheave in beam K for chain I to render round, held by pin E', Figs. 1, 2, 3. Chain I connects the levers g g, Figs. 1 and 2, by being fastened to the ends of levers g g by bolts Z Z, Figs. 1 and 2, said bolts being screwed into the ends of levers at D' D'.

L is a rope fastened to bolt Z', Fig. 2, passing under sheave M up to windlass N, sheave M being loose on bolt F'', which passes through the end of beam K and frame-piece A'', Fig. 4, the windlass N being held in place by upright pieces T T, which are fastened to frame-piece a', Figs. 1 and 4. The windlass N is provided with a ratchet-wheel, O, Figs. 3 and 4.

P is the lever, and is provided with a pawl, X, Fig. 4, which, when lever P is raised, will drop of its own gravity into the teeth of ratchet-wheel O, and when lever P is depressed will turn cylinder N and wind up rope L.

W is a pawl, Figs. 3 and 4, which is fastened to press-box at f'', Fig. 4, and drops in the teeth of ratchet O and prevents the windlass N from turning backward when pressing.

B is the top beam, and e the lid fastened to beam B, and hinged at H, Fig. 1, so that it can be raised and lowered at pleasure. Beam B is fastened down by rods D D, Figs. 1 and 4, which pass over the beam B to prevent it from rising. D D also prevent the bottom beam from lowering when pressing.

U is a crank on the shaft of windlass N, by which the press, levers, and beam E are lowered after the bale is pressed.

Q is one door hinged to frame-piece a'', Fig. 4, and is let down. The other door is not shown.

R R R R, Fig. 3, are the hinges that carry doors Q, on which they turn. R' R' R' R' R', Figs. 1 and 4, are slots or recesses in the follow-board and top lid, that allow the ropes or hoops to pass round to secure the bale when pressed.

V, Fig. 3, is a lever by which the top lid is raised to a vertical position.

Having thus described the different parts of the press, I will now describe its operation. Suppose follower E F to be down, as shown by the red marks, Fig. 1, to nearly a horizontal

position. Then the doors Q, Fig. 4, are shut, and the top lid raised to a vertical position by liberating rods D D and pulling down the top lever, V, it turning on its hinges at H H, Fig. 1. The doors Q, Fig. 4, are held by hooks S S S S, as shown. The box is now ready to be filled. When this is done, the top lid is let down and secured by rods D D over the ends of the beam B, Fig. 4. Now, by raising lever P pawl X will drop in the teeth of ratchet O, and by pulling down lever P the windlass N, Fig. 3, will turn and wind up the rope L, which, being fastened to the lever g at D'', Fig. 2, by bolt Z, the connecting-chain I being fastened to the same bolt and passing round sheave J to lever g at D'', will pull both levers at the same time in opposite directions and pass from D'' to D' and from D'' to D''', as shown in Figs. 1 and 2, which will place them in the position as shown by black levers standing vertically in Fig. 1, which will complete the pressing of the bale. The hooks S S S S must be raised and the doors Q Q, Fig. 4, must be let down. The ropes or hooks may be passed through the recesses R' R' R' R' R' R' and passed round the bale and tied or fast-

ened. The lever P must be dropped down by liberating the pawl X, which will leave the windlass held by pawl w from going back. Now, by taking hold of the crank u and lightly turning back windlass N, the pawl w can be raised and the windlass reversed, and the follow-beam E and levers g g h h lowered three or four inches, which will liberate the bale. After the bale is taken out of the press, the crank u may be turned back, which will lower down the beam E and the levers g g h h to position shown by red levers, Fig. 1, which will complete the operation.

I am aware that levers similar to those used by me have been used before in various ways. I therefore disclaim them in and of themselves considered; but

What I claim as new, and desire to secure by Letters Patent, is—

The levers g g h h, chain I, and sheave J, when arranged on the beams E K in the manner shown, and for the purpose set forth.

SIMON INGERSOLL.
